UNITED STATES PATENT OFFICE.

DAVID LARSON, OF YONKERS, NEW YORK, ASSIGNOR TO OTIS ELEVATOR COMPANY, OF JERSEY CITY, NEW JERSEY, A CORPORATION OF NEW JERSEY.

OVERLOAD CIRCUIT-BREAKER.

1,134,750.

Specification of Letters Patent.

Patented Apr. 6, 1915.

Application filed October 14, 1911. Serial No. 654,651.

To all whom it may concern:

Be it known that I, DAVID LARSON, a subject of the King of Sweden, residing at Yonkers, in the county of Westchester and State of New York, have invented a new and useful Improvement in Overload Circuit-Breakers, of which the following is a specification.

My invention relates to protective devices for electrical apparatus, and has for its object the provision of means for interrupting the circuit of a translating device upon excessive flow of current.

A further object of my invention is the provision of a simple, practical and efficient overload circuit breaker which may be reset from a distant point.

Other objects of the invention will appear hereinafter, the novel combinations of elements being pointed out in the annexed claims.

The drawing accompanying this specification illustrates diagrammatically a motor controlling system embodying my invention.

Referring to the drawing, I show a main line switch 10 adapted when closed to complete a circuit to a motor 70 through a starting resistance 60. The latter is controlled by the motor through an accelerating magnet 50 and contacts 1, 2, 3 and 4. The motor field is shown at 80 and an electro-magnetic brake apparatus is shown at 90, the brake operating on a brake pulley secured to the shaft 5 of the motor. The fast and slow speed magnet switch 40 controls a circuit to the accelerating magnet 50 through the normally open contact 5. The magnet switch 40 and the main line switch 10 are both controlled by a master switch 20. The overload relay is designated by 30.

Having given a general description of the various parts, I will now give a more detailed description and point out the various electrical circuits associated therewith.

The main line switch 10 comprises a solenoid 6 which when energized is adapted to raise a core 7, thereby closing the contacts 8 and 9. The contacts 8 control a circuit to the motor while the contacts 9 control a circuit to the releasing solenoid of the brake 90. The overload relay 30 comprises one or more cores such as 17 and 17' and a low and high resistance winding 15 and 16 respectively, the cores being connected together and to one of a pair of normally

closed contacts 18, a regulating screw 19 being provided for the purpose of adjusting the core 17 with respect to its magnet winding 15. The master switch 20 comprises a lever 11 adapted manually to be moved into electrical engagement with the contact strips 12, 13 and 14.

The operation of the apparatus just described is as follows: Upon moving the lever of the master switch into a position indicated by the broken line *a*, the contact strips 12 and 13 are short circuited and a circuit is closed to the winding 6 of the main line switch 10, this circuit being traced from the line to the contact strips 12 and 13, solenoid 6, contacts 18, and by the conductor 21 to the main. The main line switch 10 is now energized to close its contacts 8 and 9 which establishes a circuit to the motor 70 and the releasing magnet of the brake 90, the shunt field 80 being at the same time connected across the line. The motor now starts to rotate, its speed being limited by the starting resistance 60 which is in series therewith. The lever of the master switch 20 is next moved over until it assumes a position indicated by the broken line *b* and the magnet winding of the fast speed switch 40 becomes energized, its circuit being closed at the contact strip 14. The switch 40 now operates to close its contacts 5, thereby connecting the accelerating magnet 50 in a circuit which is in parallel to the motor armature and a small portion of the starting resistance 60. As the motor is now running and generating a counter-electro-motive force, the accelerating magnet 50 will operate its contacts 1, 2, 3 and 4 in the order named, gradually to short circuit the resistance 60 and permit the motor to run up to its full normal speed. It will be observed that the armature circuit includes the low resistance winding 15 of the overload relay 30 and the current in this winding tends to raise the core 17 and open the contacts 18. By means of the screw 19, however, the core 17 is so positioned with respect to the winding 15 that the core will not move upwardly except and until the current flowing to the motor becomes excessive and the motor is overloaded. When an overload does take place the core 17 is raised and the contacts 18 become separated and the high resistance winding 16 is inserted in series with the solenoid 6 of the main line 110

switch 10. The resistance of the solenoid 16, however, is so high that the current in the magnet of the main line switch is reduced to such an amount that it no longer is able to maintain the switch in closed position and the latter drops its contacts thereby opening the motor and brake circuits and the motor comes to rest, the starting resistance 60 being reinserted into the armature circuit, since the accelerating magnet is now open circuited at the contacts 9. It will be observed that the action of the overload relay 30 is very quick for the reason that at the instant that the coil 17 starts to separate the contacts 18, the coil 16 is placed in circuit and the further upward movement of the cores 17 and 17' is effected by the combined action of both coils working together and from this it follows that the main line switch 10 will also operate quickly to open the motor circuit and stop the motor. As soon as the main line switch has operated the coil 15 is deprived of current but the winding 16 remains energized and is of sufficient power to retain the contacts 18 in open position. Under the present conditions the motor cannot be operated until the operator first moves the lever of the master switch back to its original or "off" position. As soon as he does that, the self-holding circuit of the overload relay magnet 16 is broken at the contact 13 and the contacts 18 of the overload switch again come into contact with each other and the system assumes its normal position of rest as shown.

The overload relay 30 arranged according to my invention, will protect a motor or any other device in circuit therewith from excessive current flow, and it offers one great advantage over circuit breakers in general in that it contains no tripping devices such as catches or triggers and furthermore may be reset ready for subsequent operation by merely centering the master switch, which latter may be located at any convenient point or at any desired distance from the rest of the system.

While my improved overload device will protect a motor or any other electrical device from an overload, it will be observed that the main line switch cannot maintain itself in closed position unless the pressure of the mains is substantially of normal potential, for it is apparent that any substantial falling off in potential of the main line will weaken the strength of the solenoid 6 to such a degree that it will not hold the switch closed and the main circuit will be interrupted at the contacts 8. Thus it is seen that my invention protects against abnormal low potential as well as against excessive current flow, for in both cases the main circuit is opened. As soon as conditions have again become normal the main circuit may be closed and if said circuit in-

cludes a motor, the starting resistance will always be included in the circuit so that it is impossible to close the motor circuit at a time when the starting resistance is short-circuited and thereby damage the motor. 70

For clearness of illustration, I have shown and described the overload relay as comprising a plurality of cores and a magnet winding for each core, but it is to be understood that a single core could just as well be used 75 in place of the two cores as shown, and the high and low resistance coils 16 and 15 respectively, could be wound one upon the other similar to the primary and secondary windings of a transformer, the windings 80 being arranged and connected so as to assist each other and not act in opposition.

What I claim and desire to have protected by Letters Patent of the United States is:—

1. The combination with a main line 85 switch, an electromagnet for moving said switch to closed position, a relay having manually closed contacts in a circuit of said electromagnet, a magnet winding for said relay arranged to effect the operation of the 90 same upon an overload, an additional magnet winding for the relay, normally short circuited by the relay contacts and adapted to assist in the operation of the relay upon the initial separation of the relay contacts, 95 and a manual switch controlling a circuit through said additional magnet winding and the winding of the main line switch in series.

2. The combination with a main line 100 switch, of an electromagnet for moving said switch to closed position, an overload relay having a low resistance winding in series with the main line switch contacts and a high resistance winding in series with the 105 magnet winding of the said main line switch, a short circuit around said high resistance relay winding normally established by the relay contacts, and a hand switch controlling a circuit to the magnet winding of the 110 main line switch in series with the contacts of the overload relay.

3. The combination with a main line 115 switch, of an electromagnet for moving said switch to closed position, an overload relay 120 having a low resistance winding in series with the main line switch contacts and a high resistance winding in series with the magnet winding of the said main line switch, a short circuit around said high resistance relay winding normally established by the relay contacts, a switch controlling a circuit to the magnet of the main line switch and thereby energize the low resistance winding of the relay, means operated by the 125 relay upon an overload opening the short circuit around the high resistance winding of the relay and thereby effect the opening of the main line switch.

4. The combination with a main line 130

switch, of an electromagnet for moving said switch to closed position, an overload relay having a series and shunt winding adapted to act cumulative, means operative upon an overload for placing said shunt winding and the magnet of the main line switch in series to effect the opening of the main line switch, and a hand switch controlling the circuit through the main line switch magnet.

10 5. The combination with a main line switch, of a magnet for closing said switch, an overload relay controlling the opening of said switch, a magnet winding associated

with said relay adapted to be energized upon the operation of the latter to hold the 1. same in operated position, and a controlling switch connecting said main line magnet and said relay holding magnet in series across the line.

In testimony whereof, I have signed my 20 name to this specification in the presence of two subscribing witnesses.

DAVID LARSON.
